UNITED STATES PATENT OFFICE.

MAURICE SIMON, OF ST. LOUIS, MISSOURI.

ELECTRIC WATER-HEATER.

1,196,487.

Specification of Letters Patent. Patented Aug. 29, 1916.

Application filed December 7, 1915. Serial No. 65,483.

To all whom it may concern:

Be it known that I, MAURICE SIMON, a citizen of the United States, residing at the city of St. Louis and State of Missouri, have invented a new and useful Electric Water-Heater, of which the following is a specification.

This invention relates to improvements in electric water heaters, and consists in the novel design and arrangement of parts hereinafter more fully disclosed.

An object of the invention is to produce an economical and efficient water heater in which the water is passed through a tortuous heating chamber in which are disposed coils of resistance wire so arranged that a volume of water passing through the chamber will be brought into direct contact with said coils.

Another object of the invention is to provide an electric water heater including a tortuous insulated chamber having heating resistance coils disposed therein, with provision for automatically controlling the electrical energizing circuit.

Another object of the invention is to provide a water heater having a heating chamber of novel design in which is disposed a continuous stretch of resistance wire arranged in coils, so that the entire volume of water passing through the heater will be brought in contact with the stretch of resistance wire and thereby become heated, with provision for breaking the electrical energizing circuit when a predetermined maximum heat has been attained.

Additional advantages and features attainable from the present invention are contemplated and their nature and character will be readily understood without specific mention from the following detailed disclosure of the invention, taken in connection with the accompanying drawings, in which—

Figure 1 is a vertical section through the heater and through the associated electrical current-controlling devices used in connection therewith. Fig. 2 is a cross section through the heater taken substantially on the line 2—2 of Fig. 1 showing the interior construction of one of the sections of the heating chamber with the resistance wire disposed therein, and illustrating in detail the construction of the thermostatic device which is part of the current control. Fig. 3 is a vertical section through the heater

substantially on the line 3—3 of Fig. 1 illustrating the back plate of the other section of the heating chamber. Fig. 4 is a diagrammatic view illustrating the electrical energizing circuit and the resistance circuit, together with the controlling devices therefor.

In the embodiment of the invention illustrated in the drawings the heater case comprises a circular back plate 1, a circular front plate 2, and intermediate circular partition plates 3 and 4, the plate 3 having an inwardly extending annular flange 5 from the inner edge of which extends a rim 6, and the plate 4 having an outwardly extending annular flange 7 from the outer edge of which extends an annular rim 8. Thus, when the plates 3 and 4 are secured together by bolts 9 passing therethrough and the plates 1 and 2 are mounted in position, two parallel chambers or compartments are formed, in each of which is arranged a tortuous duct or passage for the water. The interior surfaces of the chambers or compartments are insulated by providing an enamel coating 80 for the surfaces, or if desired separate insulating shells may be inserted within the chambers. The purpose of insulating the inner surfaces of the compartments will be apparent from the further description of the apparatus.

In order to provide means for securing the heater case to a vertical support I provide brackets 10 which are formed integral with the plate 1 through which bolts 11 may be passed for securing the heater in a vertical position. Housings 12 are provided over the plates 1 and 2, which housings form air spaces or compartments in which is packed a quantity of mineral wool 13, or other non-heat conducting material to prevent radiation of the heat from the plates. The plate 2 has formed integrally therewith a tubular extension 14 constituting an inlet for conducting the inflow of the fluid from a supply passage 15, and formed integrally with the flange 5 is a tubular extension 16 constituting an outlet passage for the outflow of the liquid from the heater, said passage being connected into a service conduit 17.

The tortuous ducts or passages formed in the chambers of the heater are intercommunicating, so that fluid entering the supply conduit 14 will be required to pass through an extended passage within the heater before passing to the outlet 16. The

tortuous passages in the chambers of the heater are formed from partition walls of insulating material, said partition walls being substantially duplicate in construction and in practice being formed from porcelain, enamel, or other suitable insulating material, and each comprising continuous helical, parallel, transverse walls 18 and 19, the alternate curves of the helix 5 formed by the walls being closed at the opposite edges by integrally formed vertical walls 20 and 21. The walls 18 and 19 are integrally united at the center, there being a passage 22 through the walls approximately at the point of union thereof. 10 When the partition walls are mounted in the chambers in which they are held in position by clamping extensions 23 of the walls 21 between the plate 1 and the rim 6 15 and the plate 2 and the rim 8, respectively, an extended tortuous passage for the flow of the liquid is formed. The water entering through the inlet 14 flows around the outer curve of the helical passage formed 20 between the outer curve of the wall 19 and passes into the next curve of the helix between the walls 18 and 19 until it reaches the center of the heater, then passes through 25 the passage 22 and back to the periphery of the chamber from which it is conducted 30 through an opening 24 through the partition plates 3 and 4, into the adjacent chamber, flowing in a like manner therethrough and discharging through the passage 16. Forming a tortuous passage in the manner described gives an extended 35 length of flow in a compact space.

The advantage of forming the partition walls in the manner described lies chiefly 40 in the fact that the partition walls may be readily manufactured from flat sheets or plates formed in dies and an economy in material effected, as the interior of the chambers is utilized as walls of the duct. It will 45 also be noted that when the partition walls are in position the vertical end walls 20 and 21 extend adjacent to the interior of the chambers for a considerable distance so that 50 each stretch of the duct is sealed from the other, preventing seepage of the water from the normal course through the passages.

The resistance circuit which is co-extensive 55 with the tortuous water passage within the heater is formed from a continuous stretch of resistance wire 25 wound preferably in the manner illustrated in the drawings in the form of a series of helical cones oppositely disposed, and the bases thereof abutting. Thus, the resistance wire extends 60 in the conduit so that stretches thereof will be disposed in different cross sectional points so that the entire volume of water passing through the duct will be brought in contact with the resistance wire. Moreover, the enlarged curves or bulging parts 65

of the stretches at the matching bases of the conical formations serves to hold the resistance wire in position by abutting against the edges of the passage.

I do not desire to limit myself to the specific winding of the resistance wire, but I consider that the form of winding illustrated possesses advantage over a cylindrical form of winding, as it will be appreciated that in a cylindrical form of winding a current of water at the center could flow through without coming into contact with the resistance circuit, but where the stretches alternately diminish and enlarge in diameter the path of the water is intersected throughout its length by windings of the resistance wire, the resistance wire coming in direct contact with the entire volume of water passing through the duct.

A terminal binding post 26 extending out through the plate 2 is provided at one end of the resistance circuit and a terminal binding post 27 is provided at the other end of the resistance circuit. The entire energizing circuit, the resistance circuit and the controlling devices therefor are fully illustrated in Fig. 4 of the drawings. One main lead 28 of the electrical supply circuit is attached to the binding post 27. A lead 29 from the other pole of the supply circuit leads to a terminal contact plate 30 of a switch device having a complementary contact plate 31. A lead 32 leads from the contact 31 to the binding post 26 of the resistance circuit. The connection between the contact plates 30 and 31 is effected through a switch plate 33 which is supported upon a stem 34, the plate 33 being held normally out of contact with the plates 30 and 31 by a spring 35. On the opposite end of the stem 34 is an armature plate 36 which is under control of an electromagnet 37.

The electromagnet is in a shunt circuit comprising a lead 38 from the contact plate 30 to one pole of the electromagnet, the shunt circuit being complete through a lead 39 from the other pole thereof leading to a thermostatic device 40, the details of which will be described hereinafter, which acts as a circuit breaker normally maintaining the lead 39 in electrical connection with a lead 41, which terminates in a binding post 42 having an inwardly extending contact stem 43. The contact stem 43 is a part of a switch device under control of the fluid pressure in the supply passage. The switch device has a complementary contact member 44 having a binding post 45 from which a lead 46 terminating in the contact member 31 extends.

The circuit between the contact members 43 and 44 is completed through a plate 47 which is a part of the pressure operated device, the details of construction of which will be explained hereinafter. Suffice it to

say for the present purpose that when water is withdrawn from the heater the plate 47 contacts with the members 43 and 44. When the contact is made and the circuit completed 5 through the members 43 and 44 it will be observed that the shunt circuit, comprising the lead 38, the electromagnet 37, the lead 39, the circuit breaker 40, the lead 41 and the lead 46, is closed, as the lead 46 is in electrical connection through the lead 32 and the resistance circuit with the main lead 28 of the circuit. When the shunt circuit has thus been closed the electromagnet 37 is energized moving the armature 36 and thereby 10 the stem 34 and the plate 32 toward the electromagnet, which movement brings the plate 33 into contact with the terminal elements 30 and 31, thereby completing the main circuit and throwing a full current across from the lead 29 to the lead 32, effectively to energize the resistance circuit to the extent of the current supplied through the main line. The main circuit will remain closed so long as the shunt circuit remains closed, 15 it being observed that the shunt circuit may be opened either by operation of the device 40, or by operation of the pressure device in the supply conduit. The thermostatic device 40 is designed to operate and open the circuit when a predetermined heat has been attained within the heating chamber.

The thermostatic device comprises plates 48 and 49 secured together at their ends and mounted upon an insulated block 50, the lead 35 39 being electrically connected with said plates and the whole device being preferably mounted adjacent to the discharge outlet from the heater. The plates 48 and 49 are of different co-efficients of expansion, the 40 plate 48 having a smaller co-efficient of expansion than the plate 49. The plate 49 has attached thereto a hooked-stem 51, the end of which is adapted to engage against a spring plate 52 attached to a binding post 53 45 and insulated from the walls of the heater, said binding post having connected thereto the lead 41 of the shunt circuit.

When the heat in the chamber rises to a predetermined maximum limit the relatively 50 greater expansion of the plate 49 will bow the same outwardly sufficiently to move the stem 51 out of contact with the plate 52, thereby opening the shunt circuit, causing the electromagnet 37 to be deenergized permitting the release of the armature 36, the 55 spring 34 carrying the plate 33 out of contact with the members 30 and 31, thereby opening the main circuit. When the water in the heater has again dropped below the 60 predetermined maximum the plates 48 and 49 will return to normal position again closing both the shunt circuit and the main circuit.

The pressure operated device in the supply conduit comprises a sleeve 54 mounted

within the supply passage and incidentally constituting a union between said supply passage and the inlet passage 14. Within the sleeve 54 is mounted a ring 55 having radial arms 56 supporting at their center a 70 sleeve 57 in which is mounted a stem 58. The inner face of the ring 55 constitutes a valve seat for a valve plug 59 which is mounted upon the extremity of the stem 58. The valve plug 59 is of insulating material 75 and carries on its outer face the plate 47, through which the circuit from the terminals 43 and 44 is controlled. This construction has the following mode of operation: The valve plug 59 is normally held to its 80 seat, closing communication between the supply passage 15 and the inlet passage 14. When pressure in the inlet passage 14 is reduced by opening the discharge passage 17 from the heater, the pressure of the valve 85 in the supply passage 15 will force the valve outwardly bringing the plate 47 into contact with the members 43 and 44. When the pressure is again equalized by closing the outlet passage from the heater, a spring 60 90 encircling the stem 58 will bring the valve plug 59 to its seat and close the passage automatically.

I am aware that numerous changes may be made in the construction without departing from the spirit and scope of the invention. I do not desire to limit myself therefore to exact details shown and described, but

What I claim and desire to secure by Letters Patent is:—

1. An electric water heater comprising a heating chamber, a partition plate in said chamber forming a tortuous passage for the flow of the water therethrough, a resistance circuit comprising a stretch of resistance wire formed in coils and mounted in said passage, a main circuit for energizing said resistance circuit, and electrically controlled means under the influence of pressure in the 105 heater for making and breaking said electrical circuit for supplying said resistance circuit, substantially as specified.

2. A water heater comprising a case having adjacent compartments therein, partitions in each of said compartments forming together a communicating tortuous passage, a resistance circuit seated in said passage and comprising a stretch of resistance wire formed in united coils, an electric circuit 115 connected into said resistance circuit, a circuit-breaker in said circuit, and electrical means under control of the pressure in the heater for controlling said circuit breaker, 120 substantially as specified.

3. In an electric water heater, a tortuous heating chamber, a resistance circuit mounted in said heating chamber in direct contact with the fluid passing therethrough, a main circuit for energizing said resistance circuit, 130

- 21
- 5 a circuit breaker in said main circuit normally in open adjustment, a shunt circuit, an electrical device in said shunt circuit for controlling said circuit breaker, a thermostat in said shunt circuit adapted to make and break said shunt circuit, and a water pressure control device in said shunt circuit for making and breaking said shunt circuit, substantially as specified.
- 10 4. A water heater comprising parallel chambers, partitions in said chambers providing a tortuous passage extending from the periphery of the heater to the center and outwardly to the periphery with a communicating passage to the periphery of the adjacent chamber, a resistance circuit comprising a series of integrally united coils having turns of varying diameters mounted in said passage, a circuit for energizing said 15 resistance circuit, electrical means under the influence of heat in said chamber for controlling said energizing circuit, and additional means under the influence of pressure in said heater for controlling said circuit.
- 20 5. In a water heater, a case divided into two parallel chambers, a communicating passage between said chambers, partition walls in said chambers forming tortuous passages therein, a resistance circuit comprising a continuous stretch of resistance wire formed in coils having turns of varying diameters, a circuit for energizing said 25 resistance circuit, and means under the influence of pressure in said heater for controlling said circuit, substantially as specified.
- 30 6. In a water heater, a case divided into two parallel chambers, a communicating passage between said chambers, partition 35 walls in said chambers forming tortuous passages therein, a resistance circuit comprising a continuous stretch of resistance wire formed in coils having turns of vary-
- ing diameters, a circuit for energizing said resistance circuit, and means under the influence of the heat in said chamber for controlling said circuit, substantially as specified.
7. An electric water heater comprising parallel tortuous heating chambers, an inlet passage entering the periphery of one of said chambers, a discharge passage discharging adjacent to the periphery of the other of said chambers, a continuous resistance circuit in direct contact with fluid passing through said passage, an energizing circuit for said resistance circuit, a movable switch member in said circuit, a shunt circuit, an electromagnet in said shunt circuit adapted to control said switch member, electric means operated by pressure in said heater for energizing said shunt circuit and thereby causing said electromagnet to close the main circuit, and means under the influence of heat in the chamber for opening said shunt circuit and thereby said main circuit, substantially as specified.
8. In a water heater a tortuous heating passage, a resistance circuit comprising a stretch of resistance wire formed in coils and submerged in the water passing through said passage, an energizing circuit for said resistance circuit, means under the influence of the heat in said passage for controlling said energizing circuit, and additional electrical means operated by pressure in said heater for controlling said energizing circuit, substantially as specified.
9. In witness whereof, I have signed this specification in the presence of two subscribing witnesses.
